William J. Jackson
ATTORNEY.

UNITED STATES PATENT OFFICE

JOHN G. GIBSON, OF VENTNOR, NEW JERSEY

GRATE STRUCTURE

Application filed May 17, 1929. Serial No. 363,971.

This invention, generally stated, relates to a grate structure, and has more particular relation to that type of grate made up of bars to receive a plurality of perforated units such as are disclosed in my co-pending application for Letters Patent, Serial No. 149,565, filed November 20, 1926.

In that disclosure I make use of water grates, and in this particular case while 10 using the same structure of grates and units I discontinue the use of water in the grate and employ an air system in which cooled air is blown through the grate bars to become heated, and subsequently ejected by a nozzle 15 over the fire to better combustion and reduce the ash deposit. This may be said to be the leading object of the present invention.

A further object of the present invention resides in the provision of general details of 20 construction and in the arrangement, combination, and connection of parts for attaining the results sought by the leading object.

The invention consists of the novel construction hereinafter described and finally 25 claimed.

The nature, characteristic features and scope of the invention will be more fully understood from the following description taken in connection with the accompanying 30 drawings forming part hereof, and in which:

Fig. 1, is a view in elevation of a furnace provided with my arrangement of grate structure.

Fig. 2, is a plan view of the grate with the 35 furnace walls removed.

Fig. 3, is a view in section of the ejector nozzle.

Fig. 4, is a perspective view of one of the 40 cube-shaped units.

For the purpose of illustrating my invention I have shown in the accompanying drawings one form thereof which is at present preferred by me, since the same has been 45 found in practice to give satisfactory and reliable results, although it is to be understood that the various instrumentalities of which my invention consists can be variously arranged and organized and that my invention 50 is not limited to the precise arrangement and

organization of the instrumentalities as herein shown and described.

In the drawings the reference numeral 1 designates a plurality of spaced, hollow, 55 grate bars going to make up the grate of my invention. The opposed faces of these bars are each provided at their bottoms with continuous flanges 2 so as to support between them a plurality of air delivering units 3.

The units are preferably of cube-shape, 60 are hollow, and have open bottoms 4, and perforated domes 5. These units are provided at their bottoms with flange 6. The units are positioned between the bars so that the flanges 6 abut. The units are maintained in place by means of cementitious material. By this arrangement of cube-like air 65 units a large amount of air vents are spread generally over the grate surface, the advantage of which is apparent. The top edges of the bars are slightly bevelled and also tapered so that air jets may be spread across 70 the top surface of the grate. The reference numeral 11 designates a motor for operating a blower 12. The blower 12 has piped connection at 10 with the head pipe 13 of the furnace, which head pipe in turn is in communication by means of other pipes 14 with the grate bars in the furnace 9. The air 75 from the blower 12 passes through the grate bars and gradually becomes heated as it nears the opposed side of the furnace. Here the heated air egresses through pipes 15 to the head pipe 16 from whence it passes by pipe 80 80

17 to an ejector 18 provided with a perforated nozzle 19. The ejector is projected through the side of the furnace 9 above the grate bars so as to eject heated air across the fire bed. As the heated air under pressure is blown 85 across the fire bed complete combustion is obtained, thus reducing cost of maintenance, providing more heat units, and reducing ash deposits, it being understood that with decreased ash deposits increased efficiency of the furnace may be maintained. The reference numeral 8 designates a damper in pipe 10 so that air from the blower may be regulated as it passes to head pipe 13. By the arrangement above described I am enabled to 90

95 employ the motor grate shown in my patent 100

application aforesaid with very slight change, the advantage of which is apparent.

What I claim is:

In combination, a furnace, a head pipe for cool air arranged at one side of said furnace, a plurality of spaced hollow grate bars extended through said furnace at right angles to said head pipe, a plurality of units having open bottoms and perforated tops fitted between said grate bars, a second head pipe arranged upon the side of said furnace opposite said first mentioned head pipe and in substantially the same plane with said first mentioned head pipe, the opposite ends of said grate bars being directly connected to said head pipes for uninterrupted circulation of air, a blower connected to said first mentioned head pipe for passing cool air to said grate bars, a profusely perforated nozzle extended through a side wall of said furnace in a plane above and parallel with said grate bars, and a pipe connection from said second mentioned head pipe to said nozzle for feeding heated air under pressure to said nozzle in a plane above and substantially parallel to the perforated tops of said units.

JOHN G. GIBSON.
